UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

Application filed February 14, 1921. Serial No. 444,790.

The invention comprehends improvements of especial utility in the coking retort oven art; and also comprehends certain improvements applicable to coking retort ovens 5 of the well-known Koppers cross-regenerative type exemplified in the patent to H. Koppers No. 818,033 dated April 17, 1906.

The invention has for an object to provide a combination coke oven with a novel and 10 highly efficient system of combustion in the flame or combustion flues of the heating walls, to the end that the constant flame principle described and claimed in my co-pending application for Letters Patent for 15 a coking retort oven filed April 10, 1920, Serial No. 372,999 is incorporated in a coking retort oven, whether coke oven gas be employed as the oven fuel, or a special generator gas, such as producer gas. Furthermore, 20 the two gases may be burned concurrently, in which case the producer gas operates to dilute the coke oven gas. The invention retains, with all of its advantages, the regenerative system of conserving the 25 waste heat from the flues and utilizing such waste heat for preheating the air that enters the flues to support combustion of the fuel burned therein. In other words, the invention combines the regenerative system with 30 its attendant periodic reversal of flow, in such a way in the novel flue system that flame is maintained constantly in all the flues of each heating wall, regardless of whether the fuel be the coke oven gas distilled from the coal coked in the retorts or 35 oven chambers or the fuel be an alternatively employed special generator gas, such as producer gas, with the result that uniformity in temperature of the heating walls is promoted, 40 extreme temperature variations are eliminated, and the charges of coal within the several coking chambers are subjected constantly throughout their entire extent to the high temperatures of burning flames and 45 no retardation of the carbonization process results from the reversal of flow through the regenerators. By the invention, the efficiency of a coking retort oven is greatly promoted, notwithstanding the fuel employed, 50 the carbonization process is carried on more evenly, with greater facility and in a shorter time than has been heretofore possible, and temperature fluctuations throughout the system are greatly reduced.

55 In addition to the general objects recited

above, the invention has for further objects such other improvements and advantages in construction and operation as are found to obtain in the structures and devices herein-after described or claimed.

In the accompanying drawings, forming a part of this specification and showing, for purposes of exemplification, a preferred form and manner in which the invention may be embodied and practiced, but without limiting the claimed invention specifically to such illustrative instance or instances:

Figure 1 is a composite vertical sectional elevation through a coking retort oven of a type embodying features above specified and equipped with the improvements of the present invention, the view being taken on several vertical planes longitudinally of the coke oven battery for the purpose of disclosing the interior structure and indicated by 70 the section lines H—H, and F—F, and G—G of Fig. 2 and K—K and G—G of Fig. 6;

Fig. 11 is an enlarged perspective view, broken away in different vertical and horizontal planes, and illustrating the arrangement of the flues and the construction of the 5 parts in the upper portion of the heating wall.

The same characters of reference indicate the same parts throughout the several views.

In its present embodiment, the invention 10 is incorporated in a coking retort oven or coke oven battery having features of the well-known Koppers cross-regenerative type exemplified in the patent to H. Koppers hereinabove mentioned, which regenerative 15 coke oven includes in its construction cross-wise extending parallel heating walls constituted of flame or combustion flues, elongated coking chambers or ovens intermediate the heating walls and parallel therewith, and 20 crosswise extending regenerators located below the coking chambers and the heating walls and parallel therewith. For convenience, the present description will be confined to this use of the invention; features 25 of construction are, however, readily susceptible of other valuable applications; consequently, the scope of the invention is not confined to the specific use and specific embodiment herein described as an illustrative 30 example.

Referring to the drawings: There are illustrated views of a coke oven battery of the by-product type, such as has been hereinbefore mentioned, which battery embodies 35 in its construction a plurality of crosswise elongated heating walls 11 and a plurality of intermediate crosswise elongated vertical coking chambers 12. The heating walls 11 form the side walls of the respective coking 40 chambers 12, as shown more particularly in Fig. 1, and together with the coking chambers are supported by the heavy gas tight supporting walls of the series 13 and the other gas tight supporting walls of the series 45 14. Both series 13 and 14 of such supporting walls extend crosswise of the battery and are located, as shown, below the coking chambers and the heating walls, and collectively form the main support for the entire 50 super-structure of the oven battery. These supporting walls are themselves firmly supported upon a flat mat or platform which constitutes the sub-foundation on which the entire battery rests.

55 The coal to be coked is charged into the several coking chambers or ovens 12 through charging holes 15, indicated by dotted lines in the top 16 of the oven battery, positioned directly above the ovens or chambers 60 12, as shown in Fig. 1. These charging holes 15 are equipped with the usual removable covers, not shown, which are removed when charging any of the several ovens and placed in position to close the tops 65 of the ovens during the entire coking opera-

tion. The gases of distillation pass from the tops of the several coking chambers 12 through the usual gas outlets and communicably connected ascension pipes, not shown, into the usual gas collecting main which 70 carries the distillation products to the by-product recovery apparatus.

Heat for coking the charges of coal in the several ovens or chambers 12 is derived from the heating walls 11, which, as before mentioned, extend crosswise of the battery at the sides of the coking chambers. The construction and the functioning of these heating walls constitute important features of the present invention. Referring now more 80 particularly to Fig. 5, each heating wall is constituted of two series, 17 and 18, of vertical flame or combustion flues, the flues of one series 17 alternating with the flues of the other series 18. When one series of such 85 flues is operating for upflow, that is to say burning upwardly, the other series of such flues is operating for downflow, that is to say burning downwardly. Arranged along one side of the central axis of each heating 90 wall 11 and alternating with the individual flues thereof are two series of vertical channels 19 and 20, the channels of one series 19 alternating with the channels of the other series 20. Also arranged on the opposite side of the said central axis of each heating wall 11 and alternating with the individual flues thereof, are two further series 95 of vertical channels, 21 and 22, the channels of the series 21 alternating with the channels of the other series 22. With the above described construction, each heating wall 11, is equipped with two series of flame or combustion flues and with four series of vertical channels, the several series of flues and channels of each heating wall being each controllable both as to direction and character of the flow independently of the other series of channels and flues as will be more fully explained hereinafter.

The crosswise regenerators of the retort oven or battery are located below the aforesaid heating walls 11 and coking chambers 12 and in the present instance extend in parallelism between the supporting walls aforesaid. According to the invention, the supporting walls of the series 13 are grouped into pairs 23, as shown in Fig. 1 and the supporting walls of the series 14 are respectively located between individual members of such pairs, whereas the supporting walls 14 are omitted between adjacent supporting walls 13 of different pairs. Both series 13 and 14 of supporting walls form the side walls of regenerators, and, with this construction, there is thus provided a series 24 of regenerators that are respectively located between adjacent supporting walls 13 of different pairs, a series 25 of regenerators that are respectively lo- 110 115 120 125 130

cated, as viewed in Fig. 1, on the left side of their contiguous supporting walls 14, and a third series 26 of regenerators that are respectively located on the right side of their contiguous supporting walls 14.

Each regenerator is a chamber containing open brick work, commonly called checker-work, and indicated at 27, with a distributing sole channel 28 underneath such checker-work, the channels forming the soles of such chambers and opening up into the checker-work. These regenerators in alternation are heated by the hot combustion products that draw off from the flame or combustion flues hereinabove mentioned and then impart such heat to the medium that they feed into these flame flues.

In accordance with the invention, each regenerator of the series 24 is communicably connected by a series of ducts 29 with the flame flues of the series 17 of the heating wall located to the right of such regenerator, and is also communicably connected by a series of ducts 30 with the flame flues of the series 18 of the adjacent heating wall located to the left of such regenerator. In addition, each regenerator of the series 24 is communicably connected by means of a series of ducts 31 with the series 19 of vertical channels of the heating wall to the right and is also communicably connected, by means of a series of ducts 32 with the series of vertical channels 21 of the heating wall to the left. Each regenerator of the series 25 is communicably connected by means of a series of ducts 33 with the flame flues of the series 17 of a single heating wall located above such regenerator, and is also communicably connected by means of a series of ducts 34 with the vertical channels of the series 22 of the same heating wall. Each regenerator of the series 26 is communicably connected, by means of a series of ducts 35, with the heating flues of the series 18 of the single adjacent heating wall located above such regenerator, and is also communicably connected, by means of a series of ducts 36 with the vertical channels of the series 20 of the same heating wall. The purpose of the above described duct connections between the several regenerators, vertical channels and flues will appear in the hereinafter given description of the operation of the battery.

Referring more particularly to Figs. 2, 7 and 11, there are provided above the individual flues of the series 17 of each heating wall 11, a series of chambers 37 and above the flues of the series 18 a series of chambers 38. The flues of the series 17 of each heating wall respectively communicate with the chambers of the series 37 through ports 39, and the flues of the series 18 respectively communicate with the chambers of the series 38 through ports 40. As shown in Figs. 2 and 7, each of such chambers 37,

of each heating wall, is communicably connected with the adjacent chamber 38 by means of a horizontal duct 41. Thus, through the chambers 37 and 38 at the top of the flues 17 and 18 of each heating wall and the ports 39 and 40 and short horizontal ducts 41, the individual flues of the series 17 are communicably connected with the adjacent individual flues of the alternate series 18.

Referring more particularly to Figs. 4, 6 and 11, the series of vertical channels 19 of each heating wall respectively are communicably connected at their top with a series of chambers 42; the series of channels 20 are respectively communicably connected at their upper ends with a series of chambers 43; the series of channels 21 are respectively communicably connected at their upper ends with a series of chambers 44; and the series of channels 22 are respectively communicably connected at their upper ends with a series of chambers 45. Nozzles 46 connect the channels of all series of each heating wall with their respective series of communicating chambers. The series of chambers 42 are communicably connected by means of a series of ducts 47 with the series of flues 18; the series of chambers 43 are communicably connected by a series of ducts 48 with a series of flues 17; the series of chambers 44 are also communicably connected with a series of flues 17 by a series of ducts 49; and the series of chambers 45 are also communicably connected with the series of flues 18 by a series of ducts 50. With this construction, the tops of the two series of channels 20 and 21 are communicably connected individually with the individual flues of the series 17; and the tops of the two series of channels 19 and 22 are communicably connected individually with the individual flues of the series 18.

Extending crosswise of the battery, on each side of the longitudinal partition 51 and located beneath the heating wall 11 thereabove is a pair of gas channels 52 and 53. These channels 52 and 53 are for the purpose of supplying coke oven gas to the flues, when coke oven gas is the medium employed for fuel, and communicate respectively by means of a series of ducts 54 and 55 with the bottoms of the flame flues of the series 17 and 18 in the heating wall above such pair of gas channels. That is to say, the ducts 54 of the channel 52 lead into the flame flues of the series 17, and the ducts 55 of the gas channel 53 lead into the flame flues of the series 18. As shown in Figs. 1, 2, 3, 4, and 11, a series of access flues 56, in each heating wall, extend from the chambers 37 above the flue series 17 to the top of the oven battery, these access flues affording a means of communication from the top of the battery with the interior of the chambers 37 and the flues

17 therebeneath. A similar series of access flues 57 extend from the chambers 38 at the tops of the flue series 18. Further similar series of access flues 58, 59, 60 and 61 extend to the top of the battery from the series of chambers 42, 43, 44 and 45 which are respectively located at the tops of the series of vertical channels 19, 20, 21 and 22. Normally the access flues mentioned above are closed by suitable cover plates. As shown in Fig. 2, the access flues of the series 56 above the chambers 37 alternate with the access flues of the series 57 above the chambers 38. The access flues of the two series 56 and 57 may thus be grouped into pairs each pair comprising adjacent flues of both series. Between each pair of access flues 56, 57 is a vertical gas supply duct 62 extending from the top of the battery to the horizontal duct 41 that connects a pair of chambers 37 and 38. The several gas ducts 62, of each heating wall terminate, as shown in Figs. 2 and 11 in flaring nozzles 63, through which fuel gas may flow either into the series of chambers 37 and the connected flues 17 or into the series of chambers 38 and the connected flues 18. The flaring nozzle 63 of each duct is located at the top of the cross connecting duct 41 between two chambers 37 and 38, and, because of the coincidence of the greatest cross-sectional area of the nozzle with the discharge end thereof, and the inclined walls that extend downwardly in opposite directions toward the respective chambers 37 and 38, the gas may pass with facility either into the flues 17 or into the flue 18. The series of gas-supply ducts 62 in the top of each heating wall are supplied from a coke oven gas main 64 suitably supported over each heating wall, as shown in Fig. 1, and provided with a series of gas guns 65 which enter the inlets of the aforesaid ducts 62. Suitable supply means is also provided for supplying coke oven gas, at will, to the bottom coke oven gas channels 52 and 53.

With the above described construction, constant flame or combustion is maintained in all of the flame or combustion flues of each heating wall, irrespective of whether the flow is up or down in a series of such flues and irrespective of the type of gas employed as fuel. According to the present embodiment of the invention, when a series of flues 17, for example, of a heating wall is being fed with gas of either type from the bottom, the opposite series of alternate flues 18 in the same heating wall is concurrently being fed with fuel gas from the top. In this manner, upburning flames of either producer gas or an alternatively employed coke oven gas is maintained in all the flues of one series of the heating wall, while simultaneously downburning flame is maintained in all the alternate flues of the

other series of the same heating wall. Hence, throughout the battery, combustion is maintained in all of the flues, notwithstanding reversal of flow through the regenerators and in the flues, the manner of which will be hereinafter explained, with the result that each heating wall is being constantly heated from side to side of the battery and from top to bottom of the heating wall by constantly burning flames, temperature conditions are equalized throughout the battery or plant as a whole, and the coking process proceeds uniformly without interruption from end to end and from top to bottom of each coking chamber. The combined up-flame and alternate downflame in each heating wall results in a considerable extension of the capacity of the wall to maintain temperature in a vertical direction, thereby permitting an increase in the height of the heating walls, with a consequent increase in the height of the coking chambers, and their individual coking capacity.

In order to illustrate advantages and novel features of the invention and in exposition of the above general statements of operation and results, the following detailed description of both producer gas and coke oven gas operation of a coking retort oven, constructed in the manner above described and illustrated in the accompanying drawings is now given.

The operation of the battery, when using a special generator gas, such as ordinary producer gas, is as follows: When burning producer gas as the battery fuel, alternate regenerators of the series 24 operate as inflow producer gas regenerators; the adjacent regenerators of the series 26 and 25 which are respectively located on the left and the right of the inflow producer gas regenerators, operate concurrently as inflow air regenerators. The remainder of the regenerators of the series 24, 25 and 26 operate concurrently as outflow regenerators. For convenience in description, the inflow producer gas regenerators of one reversal period are designated on the drawings by the reference character P, the inflow air regenerators of the series 26 and 25 are designated by the reference character A, the outflow regenerators of the series 25 and 26 are designated by the reference character W, and the outflow regenerators of the series 24 are designated by the reference character E. As stated, the inflow producer gas regenerators P alternate with the outflow regenerators E, and the air regenerators A are respectively located on opposite sides of the alternately arranged producer gas regenerators P.

With the parts operating as above stated, the producer gas flows into the several producer gas regenerators P, while air flows into the several air regenerators A. As each producer gas regenerator supplies the upburning flues of two heating walls respectively

located on the right and the left of such producer gas regenerators as well as one series of vertical channels of each heating wall, the producer gas regenerators are made of 5 substantially twice the capacity of the air regenerators, the latter feeding the upburning flues and one series of channels of only a single heating wall. The producer gas from the regenerators P flows into flues of the series 17 of the heating walls to the right of such regenerators and also into the flues of the series 18 of the heating walls to the left of such regenerators, the series of flues 17 and 18 of such right and left heating walls 10 operating as upburning flues. The air regenerators A of the series 25 supply the upburning flues 17 which are located in the right side of the heating walls, and the air regenerators A of the series 26 supply the 15 upburning flues 18 which are located in the left side heating walls with respect to each producer gas regenerator P. Thus the series of flues 17 of alternate heating walls are burning upwardly, while the series of flues 18 of heating walls that are intermediate such alternate heating walls aforesaid are burning upwardly.

During this operation, the series of channels 19 of the alternate heating walls containing the upburning flues 17 are operating as upflow channels and are receiving producer gas from the ducts 31 of the producer gas regenerators; concurrently the vertical channels 21 of the intermediate heating walls containing the upburning flues 18 are operating as upflow channels and are receiving producer gas from the ducts 32 of said producer gas regenerators. The air regenerators A of the series 25 are feeding the 20 vertical channels of the series 22 of the said alternate heating walls and the air regenerators of the series 26 are feeding the vertical channels 20 of the said intermediate heating walls. In the alternate heating walls the waste gases from the upburning flues 17 pass 25 into the chambers 37 and thence through the horizontal ducts 41 into the chambers 38 and downburning flues 18; in the said intermediate heating walls, the waste gases from the upburning flues 18 pass into the chambers 38 and thence through the ducts 41 into the chambers 37 and downburning flues 17. The channels of the series 19 of the alternate heating walls feed producer gas to the chambers 42 and thence through the ducts 47 to the downburning flues 18, while the channels 50 of such alternate heating walls feed air to the chambers 45 and thence through the ducts 50 to said downburning flues 18. In the intermediate heating walls the producer gas to the downburning flues 17 is supplied to the channels 21, chambers 44 and ducts 49 and the air from the channels 20, chambers 43 and ducts 48. Consequently alternate flues 55 of every heating wall are upburning while

the other flues are downburning, there being a continual supply of producer gas and air whether from the bottom of the flue or from the top of each flue of each heating wall.

Part of the waste products from the upburning flues 17 of the alternate heating walls pass into the ducts 49 and 48 and thence into the chambers 44 and 43 and downwardly through the channels of the series 21 and 20. In the intermediate heating walls part of the waste products from the upburning flues 18 pass through the ducts 50 and 47 into the chambers 45 and 42 and thence downwardly through the channels 22 and 19. The waste gas regenerators E 70 receive the waste gas downflow from the flue series 18 of the alternate heating walls, which are located on the left of such waste gas regenerators and also from the series of channels 21; such waste gas regenerators also receive the waste gases from the flues 17 and channels of the series 19 of the intermediate heating walls on the right of such regenerators. The waste gases from the downburning flues 18 and downflow channels 20 of the alternate heating walls pass into the waste gas regenerators of the series 26, and the downflow from the downburning flues 17 and downflow channels 22 of the intermediate heating walls passes into the 75 waste gas regenerators of the series 25.

On reversal of the battery, the several regenerators of the series P become waste gas regenerators together with their connected series of flues and channels; the several regenerators E with their connected series of flues and channels become inflow producer gas regenerators; the several regenerators of the series A with their connected series of flues and channels become outflow waste gas regenerators; and the several regenerators of the series W with their connected series of flues and channels become inflow air regenerators. The reversal of the battery is accomplished by means of the usual reversing mechanism employed by those skilled in the art.

When employing coke oven gas as the battery fuel, air instead of producer gas is allowed to flow into the inflow operating regenerators of the series 24. This furnishes the larger volume of air required for the combustion of the relatively richer coke oven gas, inasmuch as the supply of air from the inflow regenerators of the series 24 is in addition to that furnished by the air regenerators A of the series 25 and 26. The flow, when operating with coke oven gas, through the several flues and channels is exactly the same as that which takes place in producer gas operation. Consequently it is not necessary to trace out the flow of the air and waste heat through the channels and flues in coke oven gas operation. During coke oven gas operation, the coke oven gas ducts 100

52 and 53 supply coke oven gas to the up-burning flues of the series 17 and 18 of the respective alternate and intermediate heating walls; the coke oven gas is drawn 5 through the ducts 62 into the downburning flues 18 and 17 of said respective alternate and intermediate heating walls. On reversal of the battery, the flow is reversed in exactly the same way as in producer gas operation, 10 that is to say, the air regenerators become waste gas regenerators and the waste gas regenerators become air regenerators, the up-burning flues 17 become downburning flues and downburning flues 18 become upburning flues. 15

Because of the fact that some of the waste gas enters the top of the downburning flues, whether the oven be operated with producer gas or coke oven gas, the flames in the down-burning flues are consequently lengthened. 20 This has the effect of increasing the volume of flame of such down burning flues and consequently increases the flame heated area of the heating walls. Such lengthening of the flames permits the making of very high heating walls, while preserving substantially uniform temperature conditions throughout a substantial extent of such walls. The lengthening of the 25 flame in the downburning flues, moreover, prevents an intense flame concentration in the upper extremities of the heating flues where it is most desirable to keep the temperature relatively low, in order to avoid 30 destruction of the gases of distillation which arise from the charge of coal in the coking chambers between the heating walls.

Furthermore, the coke oven gas may be supplied to both the upburning and down-burning flues, in which case the producer 40 gas supplied to both such series of flues functions as a diluent to the coke oven gas. Or the coke oven gas may, at will be supplied only to upburning and downburning flues. The waste gas may be regulably supplied to the downburning flues to further dilute the flames in such flues.

Although, as it above appears, the reversal of flow through the battery takes place longitudinally thereof, instead of crosswise of the battery as described in the patent to H. Koppers hereinbefore mentioned, it is nevertheless preferable to employ, crosswise of the battery, pairs of end to end positioned 55 regenerators, the regenerators of each pair respectively extending from opposite sides of the battery inwardly to the central dividing partition 51, shown in Figs. 2, 3, and 4. This construction reduces the length of 60 the regenerators crosswise of the battery and the volume of flow which must pass through each regenerator per unit of time, and thereby facilitates control of the flow through the regenerator and promotes 65 equality and distribution through the flues

and channels connected with the regenerator.

The invention as hereinabove set forth is embodied in a particular form of construction, but may be variously embodied within the scope of the claims hereinafter made.

I claim:

1. In a coking retort oven, in combination: a coking chamber; heating walls contiguous to such coking chamber and respectively constituted of a series of upburning and a series of downburning combustion flues communicably connected with and alternately positioned with respect to such upburning flues, and also of a series of upflow 75 fuel gas channels, a series of upflow air channels and two series of downflow waste gas channels, the series of said channels being disposed into pairs which alternate with the aforeaid combustion flues and the fuel 80 gas and air channels being communicably connected with the downburning combustion flues and both series of waste gas channels with the upburning combustion flues; substantially as specified. 85

2. In a coking retort oven, in combination: a coking chamber; heating walls contiguous to such coking chamber and respectively constituted of a series of upburning and a series of downburning combustion 90 flues communicably connected with said upburning flues, and also of a series of upflow fuel gas channels, a series of upflow air channels and two series of downflow waste 95 gas channels, the fuel gas and air channels being communicably connected with the downburning combustion flues and both series of waste gas channels with the upburning combustion flues; substantially as specified. 100

3. In a reversibly-regenerative coking retort oven battery, in combination: a plurality of coking chambers; heating walls contiguous to said coking chambers and respectively constituted of a series of upburning and a series of downburning combustion flues communicably connected with and alternately positioned with respect to said upburning flues, and also of a series of upflow 110 fuel gas channels, a series of upflow air channels and two series of downflow waste gas channels, the series of said channels being disposed into pairs which alternate with the aforesaid combustion flues, and the fuel 115 gas and air channels being communicably connected with the downburning combustion flues and both series of waste gas channels with the upburning combustion flues; and a crosswise regenerative system located below the coking chambers and heating walls and constituted of a series of inflow air regenerators respectively communicably connected with the upburning flues and the upflow air channels of an adjacent heating 120 wall, of a series of outflow waste gas re- 125

generators respectively communicably connected with the downburning flues and one series of waste gas channels of an adjacent heating wall, and of a further series of regenerators respectively of substantially twice the capacity of the aforesaid other regenerators and grouped into inflow fuel gas regenerators respectively communicably connected with the upburning flues and upflow fuel gas channels of two adjacent heating walls and outflow waste gas regenerators respectively communicably connected with the downburning flues and the other series of waste gas channels of two adjacent heating walls; the series of air regenerators with their communicably connected flues and channels being interchangeably reversible with the series of waste gas regenerators and their communicably connected flues and channels, and the said groups of regenerators of the further series and their communicably connected flues and channels being also interchangeably reversible with respect to each other; substantially as specified.

4. In a coking retort oven battery, in combination; a plurality of coking chambers; heating walls contiguous to said coking chambers and respectively constituted of a series of upburning and a series of downburning combustion flues communicably connected with said upburning flues, and also of a series of upflow fuel gas channels, a series of upflow air channels and two series of downflow waste gas channels, the series of said channels being disposed into pairs which alternate with the aforesaid combustion flues, and the fuel gas and air channels being communicably connected with the downburning combustion flues and both series of waste gas channels with the upburning combustion flues; and a crosswise preheating system located below the coking chambers and heating walls and constituted of a series of inflow air preheaters respectively communicably connected with the upburning flues and the upflow air channels of an adjacent heating wall, and of a further series of preheaters respectively of substantially twice the capacity of the aforesaid other preheaters and grouped into inflow fuel gas preheaters respectively communicably connected with the upburning flues and upflow fuel gas channels of two adjacent heating walls; substantially as specified.

5. In a coking retort oven battery, in combination; a plurality of coking chambers; heating walls contiguous to said coking chambers and respectively constituted of a series of upburning and a series of downburning combustion flues communicably connected with said upburning flues, and also of a series of upflow fuel gas channels, a series of upflow air channels and two series

of downflow waste gas channels, the fuel gas and air channels being communicably connected with the downburning combustion flues and both series of waste gas channels with the upburning combustion flues; and means for utilizing the heat of the waste gases to effect the preheating of the inflowing gases; substantially as specified.

6. In a reversibly-regenerative coking retort oven battery, in combination: a plurality of coking chambers; heating walls contiguous to said coking chambers and respectively constituted of a series of upburning and a series of downburning combustion flues communicably connected with said upburning flues, and also of a series of upflow fuel gas channels, a series of upflow air channels and two series of downflow waste gas channels, the fuel gas and air channels being communicably connected with the downburning combustion flues and both series of waste gas channels with the upburning combustion flues; and a crosswise regenerative system located below the coking chambers and heating walls and constituted of a series of inflow air regenerators respectively communicably connected with the upburning flues and the upflow air channels of an adjacent heating wall, of a series of outflow waste gas regenerators respectively communicably connected with the downburning flues and one series of waste gas channels of an adjacent heating wall, and a further series of regenerators respectively of substantially twice the capacity of the aforesaid other regenerators and grouped into inflow fuel gas regenerators respectively communicably connected with the upburning flues and upflow fuel gas channels of two adjacent heating walls and outflow waste gas regenerators respectively communicably connected with the downburning flues and the other series of waste gas channels of two adjacent heating walls; the series of air regenerators with their communicably connected flues and channels being interchangeably reversible with the series of waste gas regenerators and their communicably connected flues and channels, and the said groups of regenerators of the further series and their communicably connected flues and channels being also interchangeably reversible with respect to each other; substantially as specified.

7. In a reversibly-regenerative coking retort oven battery, in combination: a plurality of coking chambers; heating walls contiguous to such coking chambers and respectively constituted of upburning and downburning combustion flues, and also of upflow fuel gas, upflow air and downflow waste gas channels, the fuel gas and air channels being communicably connected with the downburning combustion flues and the waste gas channels with the upburning combustion

- flues; and a crosswise regenerative system embodying fuel gas, air and waste gas regenerators, the fuel gas and air regenerators being communicably connected with the
5. upburning combustion flues and respectively with the upflow fuel gas and air channels, and the waste gas regenerators being communicably connected with the waste gas channels and the downburning combustion
- 10 flues; the last mentioned regenerators and their connected flues and channels being interchangeably reversible with respect to former; substantially as specified.
8. In a coking retort oven battery, in combination: a plurality of coking chambers; heating walls contiguous to such coking chambers and respectively constituted of upburning and downburning combustion flues, and also of upflow fuel gas, upflow
- 15 air and downflow waste gas channels, the fuel gas and air channels being communicably connected with the downburning combustion flues and the waste gas channels with the upburning combustion flues; and a cross-
- 20 wise regenerative system embodying regenerators adapted to preheat fuel gas and air, the fuel gas and air regenerators being communicably connected with the upburning combustion flues and the upflow fuel gas
- 25 and air channels; substantially as specified.
9. In a reversibly-regenerative coking retort oven battery, in combination: a plurality of coking chambers; heating walls contiguous to such coking chambers and re-
- 30 spectively constituted of upburning and downburning combustion flues, and also of upflow fuel gas, upflow air and downflow waste gas channels, the fuel gas and air channels being communicably connected
- 35 with the downburning combustion flues and the waste gas channels with the upburning combustion flues; and a regenerative system embodying fuel gas, air and waste gas regenerators, the fuel gas and air regenerators
- 40 being communicably connected with the upburning combustion flues and respectively with the upflow fuel gas and air channels, and the waste gas regenerators being communicably connected with the waste gas
- 45 channels and the downburning combustion flues; the last mentioned regenerators and their connected flues and channels being interchangeably reversible with respect to former; substantially as specified.
- 50 10. In a reversibly-regenerative coking retort oven battery, in combination: a plurality of coking chambers; heating walls contiguous to such coking chambers and respectively constituted of upburning and downburning combustion flues, combined with a crosswise regenerative system embodying regenerators for supplying air and fuel gas concurrently to both the upburning and downburning flues of each heating
- 55 wall and other regenerators for receiving
- the waste gases from both such series of combustion flues; said sets of regenerators being interchangeably reversible substantially as specified.
11. In a coking retort oven battery, in combination: a plurality of coking chambers; heating walls contiguous to such coking chambers and respectively constituted of upburning and downburning combustion flues, combined with a crosswise preheater
- 60 system embodying a preheater for supplying air and fuel gas concurrently to both the upburning and downburning flues of each heating wall; substantially as specified.
12. In a reversibly-regenerative coking re-
- 65 tort oven battery, in combination: a plurality of coking chambers; heating walls contiguous to such coking chambers and respectively constituted of upburning and downburning combustion flues, combined with a regenerative system embodying regenerators for supplying air and fuel gas concurrently to both the upburning and downburning flues of each heating wall and other regenerators for receiving the waste
- 70 gases from both such series of combustion flues; said sets of regenerators being interchangeably reversible substantially as specified.
13. In a coking retort oven battery, in combination: a plurality of coking chambers; heating walls contiguous to such coking chambers and respectively constituted of upburning and downburning combustion flues, combined with a preheater system embodying a preheater for supplying air and fuel gas concurrently to both the upburning and downburning flues of each heating
- 75 wall; substantially as specified.
14. In a coking retort oven battery, in combination: a plurality of coking chambers; heating walls contiguous to such coking chambers and respectively constituted of upburning and concurrently downburning combustion flues; combined with a pre-
- 80 heater system for supplying an extraneously derived fuel gas and air to both the upburning and downburning flues of each heating wall; substantially as specified.
15. In a reversibly-regenerative coking re-
- 85 tort oven battery, in combination: a plurality of coking chambers; heating walls contiguous to such coking chambers and respectively constituted of series of upburning and concurrently downburning combustion flues, the flues of one series being interchangeably reversible with respect to the flues of the other series, combined with a regenerative system embodying fuel gas and air regenerators and waste gas regenerators
- 90 communicably connected with said flues; said sets of regenerators being interchangeably reversible substantially as specified.
16. In a reversibly-regenerative coking re-
- 95 tort oven battery, in combination: a plu-

- rality of coking chambers; heating walls contiguous to said coking chambers and respectively constituted of series of upburning and concurrently downburning combustion flues, the upburning series of flues being interchangeably reversible with the downburning series of flues, an interchangeably reversible regenerative system embodying regenerators communicably connected with both series of said flues, some of the regenerators being operable as inflow regenerators for supplying an extraneously derived gas to both series of said flues, and means for alternatively supplying coke oven gas to said flues; substantially as specified.
17. In a coking retort oven battery, in combination: a plurality of coking chambers; heating walls contiguous to said coking chambers and respectively constituted of series of upburning and concurrently downburning combustion flues, means for utilizing the heat of the waste gases to effect the preheating of the inflowing gases, said means being adapted to supply an extraneously derived gas to both series of said flues, and means for alternatively supplying coke oven gas to said flues; substantially as specified.
18. In a reversibly-regenerative coking retort oven battery, in combination: a plurality of coking chambers; heating walls contiguous to said coking chambers and respectively constituted of series of upburning and concurrently downburning combustion flues, the upburning series of flues being interchangeably reversible with the downburning series of flues, an interchangeably reversible crosswise regenerative system embodying regenerators communicably connected with both series of said flues, some of the regenerators being operable as inflow regenerators for supplying an extraneously derived gas to both series of said flues, and means for alternatively supplying coke oven gas to said flues; substantially as specified.
19. In a coking retort oven battery, in combination: a plurality of coking chambers; heating walls contiguous to said coking chambers and respectively constituted of series of upburning and concurrently downburning combustion flues, a crosswise regenerative system embodying regenerators communicably connected with both series of said flues, some of the regenerators being operable as inflow regenerators for supplying an extraneously derived gas to both series of said flues, and means for alternatively supplying coke oven gas to said flues; substantially as specified.
20. In a coking retort oven battery, in combination: a plurality of coking chambers; heating walls contiguous to such coking chambers and respectively constituted of upburning and downburning combustion flues, with means for supplying regulable quantities of waste gas to the downburning flues, combined with a preheater system for supplying air and an extraneously derived fuel gas to the upburning and downburning flues; and means for concurrently supplying, at will, coke oven gas to either one or both of such series of upburning and downburning flues; substantially as specified.
21. In a coking retort oven battery, in combination: a plurality of coking chambers; heating walls contiguous to such coking chambers and respectively constituted of upburning and downburning combustion flues, with means for supplying neutral gaseous diluent to the downburning flues, combined with a preheater system for supplying air and fuel gas concurrently to both the upburning and downburning flues of each heating wall; substantially as specified.
22. In a coking retort oven battery, in combination: a plurality of coking chambers; heating walls contiguous to said coking chambers and respectively constituted of series of upburning and concurrently downburning combustion flues, a regenerative system embodying regenerators communicably connected with both series of said flues, some of the regenerators being operable as inflow regenerators for supplying an extraneously derived gas to both series of said flues, and means for concurrently supplying coke oven gas to said flues; substantially as specified.
23. In a coking retort oven battery, in combination: a plurality of cooking chambers; heating walls contiguous to said cooking chambers and respectively constituted of series of upburning and concurrently downburning combustion flues, a regenerative system embodying regenerators communicably connected with both series of said flues, some of the regenerators being operable as inflow regenerators for supplying an extraneously derived gas to both series of said flues, and means for concurrently supplying coke oven gas at will to either one or both of such series of upburning and downburning flues; substantially as specified.
24. In a coking retort oven battery, in combination: a plurality of coking chambers; heating walls contiguous to such coking chambers and respectively constituted of series of upburning and downburning combustion flues, with means for supplying, at will, regulable quantities of waste gas to the downburning flues, combined with a preheater system for supplying air and an extraneously derived fuel gas to the upburning and downburning flues; and means for concurrently supplying, at will, coke oven gas to either one or both of such series of upburning and downburning flues; substantially as specified.

In testimony whereof I have hereunto set my hand.

JOSEPH VAN ACKEREN.
